UNITED STATES PATENT OFFICE

EDWIN B. NORMINGTON, OF SACRAMENTO, CALIFORNIA

LINE TAPPER

Application filed August 25, 1927. Serial No. 215,382.

This invention relates to line tappers.

The object of the invention is the production of a simple and efficient device for making connections on high voltage wires.

5 Another object of the invention is the construction of a line tapper, which can be easily connected to or fastened upon high voltage wires by means of operating devices.

With these and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a perspective view of my line tapper, mounted upon the operating device.

Figure 2 is a view in side elevation of the 20 line tapper.

Figure 3 is a vertical, central sectional view of the line tapper.

Figure 4 is a view in rear elevation of the line tapper.

25 Figure 5 is a sectional view taken on line 5—5, Figure 2, and looking in the direction of the arrows.

Figure 6 is a sectional view taken on line 6—6, Figure 5, and looking in the direction 30 of the arrows.

Figure 7 is a perspective view of the auxiliary jaw.

Referring to the drawings by numerals, 1, Fig. 1, designates my line tapper, 2 is the operating device, and 3 is the hook device.

35 My line tapper 1 comprises a primary jaw 4, upon which is mounted movable auxiliary jaw 5. The primary jaw 4 comprises a vertical body 6 that has an elongated inverted

40 substantially U-shaped upper end 7. The auxiliary jaw 5 comprises a plate-like horizontal body 8, supported upon the upper end of angle, flat spring 9; the upper end of

45 spring 9 is set into the body 8 as clearly shown in Figure 7, with the lower end fastened by screws 10 against the inner face of body 6. In the inner face of body 8 is a longitudinally extending socket 11 for receiving the wire 12, Figure 1. In the upper edge of body 8 are transverse sockets 13, 13. On the

inner face of the upper end of the primary jaw is a horizontal socket 11^a that registers with socket 11. I employ two special screws 14; each screw 14 is provided with a spindle 15 (Fig. 6) having one end seated in socket 16 and at its other end is an enlarged threaded portion 17. The spindles 15 of screws 14 are positioned in the transverse sockets or notches 13, for the purpose of preventing wire 12 from going too far up in my line tapper. 55 In other words, these screws 14 make it possible for wire 12 to be quickly seated in the sockets or grooves 11 and 11^a; also, the spindles 15 of screws 14 prevent any injurious end-wise play of the auxiliary jaw 5, keeping said jaw properly centered at all times upon the primary jaw and thereby producing a very efficient device.

A cam 18 is pivotally mounted at 19 upon the primary jaw, with its inner end extending 70 into said jaw against the spring 9 of the auxiliary jaw 5, whereby when hook device 3 (Fig. 1) is "hooked" into the aperture or "eye" 20 in the outer end of cam 18, and a downward pull is exerted upon the hook device 3, the cam 18 will be pressed against the auxiliary jaw, thereby causing the body 8 to tightly clamp wire 12 within the sockets 11 and 11^a. 75

A wire 21 is connected, at 22, to the lower 80 end of primary jaw 4.

When my line tapper 1 is mounted upon the operating device 2, it can be quickly placed upon a wire such as 12, and then through the use of hook device 3, the line tapper can be 85 securely fastened upon the wire. The detail structure of operating device 2 is illustrated and described in my United States Patent No. 1,687,584, issued October 16, 1928.

It is to be understood that the cam 18 is 90 pivotally mounted in an elongated slot 23, formed in the body 6 of the primary jaw 4 (Fig. 3).

While I have described the preferred embodiment of my invention and illustrated the same in the accompanying drawings, certain minor changes or alterations may appear to one skilled in the art to which this invention relates during the extensive manufacture of the same, and I, therefore, reserve the right 95 100

to make such changes or alterations as shall fairly fall within the scope of the appended claims.

What I claim is:

- 5 1. In a line tapper, the combination of a primary jaw provided with an upper wire-receiving end, said wire-receiving end provided on its inner face with spindle-receiving sockets, screws provided with spindles on said upper wire-receiving end of the primary jaw with said spindles in said spindle-receiving sockets, a movable jaw on said primary jaw contiguous to said spindles, and an operating cam on said primary jaw and normally 10 engaging said auxiliary jaw.
- 10 2. In a line tapper, the combination of a primary jaw provided with an upper wire-receiving end, said wire-receiving end provided on its inner face with a pair of spindle-receiving sockets, a pair of screws comprising spindles with enlarged threaded outer portions, said threaded outer portions threaded into said jaw with the inner ends of said spindles seated in said spindle-receiving 15 sockets, a movable jaw on said primary jaw, said movable jaw provided near its ends with transverse sockets in which said spindles are positioned, and a cam on said primary jaw and operatively engaging said movable jaw, substantially as shown and described.
- 15

In testimony whereof I hereunto affix my signature.

EDWIN B. NORMINGTON.
